UNITED STATES PATENT OFFICE.

HORATIO SMITH, OF KIDDERMINSTER, ENGLAND, ASSIGNOR TO WILLIAM MANSELL DAINTRY, OF NEW YORK.

DESIGN FOR A CARPET.

SPECIFICATION forming part of Design No. 12,924, dated May 9, 1882.

Application filed March 14, 1882. Term of patent 3½ years. Registered in England August 29, 1881.

To all whom it may concern:

Be it known that I, HORATIO SMITH, of Kidderminster, England, have invented a new and original Design for Carpets, of which the following is a specification.

This invention relates to a new and original design for carpets and similar fabrics; and it consists in the novel grouping and configuration of parts, hereinafter more fully described.

10 The accompanying photograph illustrates a face view of a carpet having my new design.

The stripe A is composed of a band, a, with ornamentation thereon composed of a series of bars starting from the circumference of half-

15 circles set regularly along one edge of the band a, said bars having between them shorter bars with bulging ends. The stripe A also contains the band b, ornamented with a series of figures resembling deeply-serrated leaves,

20 somewhat like oak-leaves, and also contains the ornamental band d.

The stripe D has a background, X, composed of a number of fine fibers or branches apparently interlacing with each other and

25 resembling sea-weed. Upon this background appears the figure F, resembling a branch of sea-weed, with fan-shaped serrated leaves and slender sprays projecting therefrom; also, the figure E, resembling a branch of sea-weed, with

30 oval serrated leaves and slender sprays apparently springing from a central stem. The stripe D also contains the figure B, resembling a small bush with slender projecting branches.

The band C contains an ornamentation consisting of a series of circular figures with horn-like projections at the top, each series of horns containing a small ball-shaped figure. 35

The background X, above described, has been described and claimed by me in a design patent allowed to me March 29, 1882, and 40 therefore I do not here claim said background.

I claim—

1. The design for carpets, consisting of the band b, substantially as shown.

2. The design for carpets, consisting of the 45 stripe A, containing figures a b d, substantially as shown.

3. The design for carpets, consisting of the figure F, substantially as shown.

4. The design for carpets, consisting of the 50 stripe D, containing figures F B E X, substantially as shown.

5. The design for carpets, consisting of the band C, substantially as shown.

6. The design for carpets, consisting of the 55 stripe A, containing figures a b d, stripe D, containing figures F E B X, and band D, substantially as shown.

The foregoing specification of my invention signed by me this 3d day December, 1881.

H. SMITH.
